Res. 401

Reuben J. Blanchard of Albany, N.Y.
(designer to Remond & Thaxter)
Letter Patent dated July 9, 1851
No. 401...

The Schedule referred to in these Letters Patent and in writing part of the same

To all to whom these presents may come

Know ye that I Reuben J. Blanchard of the city & county of Albany
and State of New York have invented & produced a new and useful
original design being an ornament to be cast on the cast iron
plates of a stove and I do declare that the following is a full &
exact description thereof reference being had to the annexed draw-
ings which form a part of this specification

The parts of the stove upon which said ornamental de-
sign is to be placed are the end plate and the top plate.
Figure 1. in the annexed drawings represents the one half of the
end plate the other half being similar and corresponding in or-
nament. Figure 2 represents one quarter of the top plate the remainder
of that plate being similar and corresponding. The design is re-
lief and consists principally of scrolls as seen in the figures
What I claim as my invention and desire to secure by Letters Patent is
the ornamental designs for ornaments upon cast iron stove plates, above de-
scribed and more fully shown in the annexed drawings

Reuben J. Blanchard
(dated July 9, 1851)
R. J. Blanchard
